UNITED STATES PATENT OFFICE

EARL L. ROBERTS, OF PITTSFIELD, MASSACHUSETTS

DESIGN FOR A BOAT

Application filed August 16, 1930. Serial No. 36,680. Term of patent 14 years.

To all whom it may concern:

Be it known that I, EARL L. ROBERTS, a citizen of the United States, residing at Pittsfield, in the county of Berkshire and State of Massachusetts, have invented a new, original, and ornamental Design for a Boat, of which the following is a specification, reference being had to the accompanying drawings, forming a part thereof, in which one end is substantially V-shaped and the other end semi-circular.

I claim:

The ornamental design for a boat, as shown and described.

EARL L. ROBERTS.
